REFRIGERATION

Ralph C. Osborn, North Canton, Ohio, assignor
to The Hoover Company, North Canton, Ohio

Application May 2, 1940, Serial No. 332,889

6 Claims. (Cl. 62—119.5)

This invention relates to the art of absorption refrigeration and more particularly to a novel absorption refrigerating machine and an unique arrangement thereof with respect to the cabinet of a domestic refrigerator.

In absorption refrigerating systems of the three-fluid type and particularly those in which the solution is circulated by a gas lift pump from the boiler to a tubular air-cooled type of absorber, a difficult problem is presented with respect to the arrangement of the system in the cabinet because of the fact that the absorber forms the bottleneck of the entire refrigerating system and must be air-cooled efficiently. All parts of the apparatus must be held within the very rigid space limitations which are imposed upon domestic refrigerating cabinets and which give rise to numerous difficulties in the design and installation of absorption refrigerating machines. Another difficulty common to systems of the type here under consideration results from the fact that the small motor and fan used to circulate the inert gas sometimes develop objectionable noises and as located heretofore it has been in a position such that a natural sounding board was formed by the back wall of the cabinet and flue, which served to amplify and distribute the inherently small amount of noise produced by the motor fan unit. The previous arrangement of the motor fan unit also objectionably increased the total depth of the cabinet structure. Other difficulties have arisen due to the practical impossibility of positioning the refrigerating unit in a perfectly level condition when it is installed in a domestic establishment. Installation of the apparatus in a non-level position occasionally interfered with proper circulation of the solution.

It is accordingly a principal object of the present invention to provide a three-fluid absorption refrigerating machine so associated with a domestic refrigerating cabinet that most efficient air-cooling of the absorber is provided, that short direct connections are provided between the various pieces of apparatus constituting the system, that the circulating unit is positioned in a manner to check noise produced thereby and particularly to avoid a sound board effect, that the solution circulating elements are so arranged as to be affected to a minimum degree by installation of the cabinet in a non-level position, that the depth of the cabinet may be reduced to a minimum value, and that the flow of air across each individual portion of the absorber is inde-

pendent of flow of air across other portions thereof.

More specifically, it is an object of the present invention to provide a three-fluid absorption refrigerating machine enclosed in a domestic refrigerator cabinet embodying a storage chamber, an underlying machinery compartment and a rear vertically extending air duct in which the absorber lies in the rear portion of the machinery compartment and slopes downwardly and rearwardly therein whereby to provide an arrangement in which cooling air passing one section of the absorber does not subsequently pass another section thereof and in which the air which has passed any one section thereof has a free and unobstructed path therefrom to the cooling air flue.

It is a further object of the invention to provide an absorption refrigerating mechanism in which the gas circulating unit is positioned in the mechanism compartment directly beneath the food storage compartment and in substantially the central portion thereof.

It is a still further object of the present invention to provide an absorption refrigerating mechanism of the type involving a gas lift circulator for the solution circuit in which the circulator is positioned adjacent the central portion of the cabinet construction and in the lower part thereof whereby the same is affected to a minimum degree by installation of the apparatus in a non-level condition.

It is a further object of the present invention to provide a refrigerating apparatus of the absorption type associated with a cabinet including a cooling chamber, an underlying mechanism chamber and an upstanding air duct in which an air-cooled absorber of the multiple conduit type is so arranged with respect to said mechanism chamber and duct that cooling air may flow vertically across each conduit and may then flow laterally to the air duct in a flow path of progressively increasing cross sectional area.

Other objects and advantages of the invention will become apparent as the description proceeds when taken in connection with the accompanying drawings, in which:

Figure 1 is a partial sectional side elevational view of a refrigerating mechanism and its associated cabinet.

Figure 2 is a broken rear elevational view showing certain details of construction of the apparatus, and

Figure 3 is a sectional view taken substantially on the line 3—3 of Figure 1 and embodying also

a partial section of certain apparatus positioned in a plane below the plane of the line 3—3.

Referring now to the drawings in detail and first to Figure 1 thereof, there is illustrated a refrigerating cabinet 1 which embodies an insulated cooling compartment 2 which is enclosed by a suitable insulated closure 3. A machinery compartment 4 underlies the cooling chamber 2 and is closed at the front by a suitable removable panel element 5 which is provided with sound insulating material 6 on its rear or inner face. The machinery chamber 4 extends beneath the insulated compartment 2 and also beneath the rear vertically extending air flue 7 which is defined by a rear panel 8. The entire cabinet construction rests upon a suitable foot supporting element 9 which is open to allow free access of cooling air into the chamber 4 and flue 7.

The top and side walls of the chamber 4 are lined with sound deadening material 10 (see Figures 1 and 3). The panel 8 may also be lined with sound deadening material in whole or in part, if desired.

Associated with the cabinet 1 there is an absorption refrigerating apparatus of the three-fluid type embodying a boiler B, an analyzer D, a tubular air-cooled condenser C, an evaporator E, a gas heat exchanger G and an inclined tubular air-cooled absorber A, a liquid heat exchanger L (see Figures 2 and 3), a solution reservoir S and a gas circulating pump F which is driven by a suitable electrical motor M. A gas burner H which is controlled by a suitable valve mechanism V is positioned to apply heat to the boiler B. The above described elements are connected by various conduits to form a plurality of gas and liquid circuits constituting a complete refrigerating system to which reference will be made in more detail hereinafter.

The above described system will be charged with a suitable refrigerant, such as ammonia, a suitable solvent therefor, such as water, and a suitable pressure equalizing medium, preferably a dense inert gas like nitrogen.

The application of heat to the boiler B liberates refrigerant vapor from the solution therein contained which vapor then passes through the analyzer and is conveyed from the analyzer to the upper portion of the condenser C by means of the conduit 20 which includes the air-cooled rectifier R. The liquid refrigerant vapor is liquefied in the condenser C and is conveyed from the bottom portion thereof into the gas inlet conduit 21 located at the bottom of the evaporator E by means of the conduit 22 which includes a U-shaped portion adapted to form a pressure balancing column of liquid in order to shield the condenser from the relatively high pressure prevailing in the conduit 21. The condenser side of the U-shaped conduit 22 is vented by means of a conduit 23 into the rich gas side of the gas heat exchanger G with which the evaporator gas discharge conduit 24 communicates.

Though the evaporator may be of any desired type, it is herein disclosed as being of the type in which a high velocity stream of gas circulates upwardly through the evaporator and serves to distribute the evaporating liquid refrigerant by the frictional drag of the gas stream which is flowing through the evaporator. A preferred construction of this particular evaporator is disclosed and claimed in the co-pending application of Milo E. Bixler, Serial No. 252,745, filed January 25, 1939, now Patent No. 2,312,619, dated March 2, 1943.

As shown herein, the evaporator conduits are encased in a suitable housing 25 in order to provide an ice tray housing and the like. The rear portion of the evaporator includes an upstanding plate 26 which is suitably bonded as indicated at 28 to portions of the evaporator conduits and serves the purpose of cooling the air within the chamber 2.

The enriched inert gas produced in the evaporator is discharged from the upper portion thereof by conduit 24 into the inner path of the gas heat exchanger from which it is conveyed by way of the conduit 30 to the bottom portion of the absorber A. The inert gas flows upwardly through the absorber A in counterflow relationship to absorbing solution flowing downwardly therethrough which is supplied from a source to be described hereinafter. The absorbing solution removes the refrigerant vapor content of the pressure equalizing medium and the resulting heat of absorption is rejected to cooling air flowing over the exterior walls of the absorber conduit A and the fins 32 attached thereto. The lean gas formed in the absorber is conveyed from the upper portion thereof into the suction side of the gas pump F by way of the conduit 33. The inert gas is then placed under pressure by the pump F and is discharged therefrom to the gas inlet conduit 21 of the evaporator E by way of the conduit 34 and the outer path of the gas heat exchanger G.

The lean solution formed in the boiler B by the generation of refrigerant vapor is conveyed therefrom to the solution reservoir S by way of the conduit 35, the liquid heat exchanger L, and the finned pre-cooling conduit 36.

The solution reservoir S is vented by means of a conduit 37 to the suction conduit 33 of the circulating fan F whereby the solution will rise in the reservoir S to the highest level possible in the system.

The solution supplied to the reservoir S is elevated therefrom into the absorber A adjacent its point of connection with the pump suction conduit 33 by means of a twin gas lift pump mechanism 39 to which pumping gas is supplied from the discharge conduit 34 of the fan by way of the conduit 40 and the inverted U-shaped conduit 41, each leg of which communicates with one leg of the twin gas lift pump 39 and below the liquid level normally prevailing therein whereby the solution is elevated into the absorber by gas lift action. The solution is drained into the pump 39 from the reservoir S by means of a conduit 42 which connects to the bottom central portion of the reservoir and to the bottom bight portion of the U-shaped conduit constituting the twin gas lift pump 39.

The solution then flows downwardly through the absorber by gravity in counterflow relationship with the pressure equalizing medium refrigerant vapor mixture which is flowing upwardly therethrough. As described heretofore, the solution absorbs refrigerant and the resulting rich solution is conveyed from the bottom portion of the absorber A to the upper portion of the analyzer D by way of the conduit 45, the liquid heat exchanger L, and the conduit 46, thus completing the absorbing solution circuit.

The arrangement of the apparatus with respect to the cabinet constitutes an important feature of the present invention and will now be described.

The rear wall of the chamber 2 is provided with an opening 50 which is arranged to be

closed by a suitable insulated panel 51 and a joint sealing gasket construction 52. The size of the opening 50 and the panel 51 are such that the evaporator E and its associated control mechanism 52 may be freely inserted into the compartment 2 through the opening 50.

The panel 51 will be made rigidly with the evaporator and other elements of the refrigerating mechanism so that the entire apparatus may be assembled with the cabinet as a unit.

The apparatus will be controlled by means of a suitable adjustable control mechanism illustrated as a control box on top of the evaporator E at 52. The control mechanism 52 will have suitable connections to the solenoid gas valve V and to the circulating motor M whereby to energize the motor and gas burner in response to a demand for refrigeration and to de-energize these elements when the refrigerating demands are met. The connections between the mechanism 52 and the elements M and V have not been shown as they per se form no part of the present invention. A preferred form of control mechanism is disclosed and claimed in the co-pending application of Curtis C. Coons, application No. 148,424, filed June 16, 1937.

As is illustrated, the gas heat exchanger is partially embedded in the rear wall of the chamber 2 and in the panel 51 whereby to leave the air flue 7 substantially unobstructed.

The absorber A comprises a plurality of generally parallel reversely inclined and serially connected conduits 55, each of which is provided with a plurality of heat rejecting fins 32 which are offset upwardly from the tubes 55 in the direction of air flow thereacross. The absorber as a whole slopes downwardly and rearwardly from the highest tube 55 to the lowest tube 55, which lowest tube terminates adjacent the panel 8 beneath the flue 7 but in the mechanism compartment 4.

The cooling air which enters the bottom portion of the chamber 4 rises substantially vertically, crosses the tubes 55 and their associated fins 32, and then turns to the right, as viewed in Figure 1, in the case of the three highest tubes 55, in order to enter the cooling flue 7. It will be noted that the quantity of air which has passed the absorber will increase as one progresses from left to right of the chamber 4, as viewed in Figure 1. Consequently, the quantity of air flowing towards the bottom of the flue 7 constantly increases from left to right, as viewed in Figure 1. However, the cross sectional area of the space between the absorber A and the bottom wall of the chamber 2 constantly increases as one progresses from left to right, as viewed in Figure 1, wherefore provision is made for the air added by each of the progressively lower absorber tubes and there is no tendency for air which has traversed one tube and its associated fins to come into contact with a subsequent and lower absorber tube and its fins; also as the quantity of air discharged from the absorber progressively increases, the cross-sectional area of the space provided to handle this air progressively increases wherefore there is no tendency to choke the air flow above the absorber, all absorber tubes receive their proper proportion of the total air flow and all receive air not previously heated by passage across an absorber tube.

The boiler-analyzer and liquid heat exchanger assembly is embedded in a block of insulating material 60 and the whole of this assembly is

positioned in the right hand corner of the compartment 4, as viewed in Figure 3, with the analyzer, which is the tallest part of this assembly, positioned forwardly of the absorber. Consequently, that portion of the boiler-analyzer liquid heat exchanger system which will underlie a small end portion of a few of the forward absorber tubes underlies those tubes which are at the greatest height within the compartment 4 and also it is the lowest portion of the boiler-analyzer assembly which is beneath the absorber tubes, consequently there is an appreciable free air space between the absorber tubes and the insulating block 60 which allows free access of cooling air to the absorber tubes without interference with the boiler-analyzer structure. The insulating block 60 prevents this air from becoming heated before the same reaches the absorber tubes.

Another feature of this arrangement is that the heater H and gas valve V are positioned remotely from the absorber tubes and the path of cooling air and, additionally, these elements are in the very front portion of the compartment 4 whereby the same may readily be reached for servicing, adjustment, and the like simply by removing the front panel 5. It is also of importance in this connection that the burner and those portions of the boiler-analyzer system which are adjacent the burner are remote from the path of air flow of the absorber, consequently these elements which form the hottest parts of the entire system are arranged so that they will not interfere with absorber cooling.

The products of combustion discharged by the burner H pass through a central flue 61 of the boiler and are then conveyed to the top portion of the duct 7 by means of a conduit 62, preferably insulated, which extends upwardly in one corner of the air duct 7. It is apparent from Figures 2 and 3 that the products of combustion discharge conduit 62 is so positioned that the same is never in a direct path of air flowing over either the absorber or the condenser.

The motor fan unit is positioned in the top central portion of the compartment 4 directly beneath the sound insulating panel 10 and is surrounded on three sides by sound insulated panels. This arrangement has been found to muffle any noise created by the motor fan unit effectively, thus eliminating a commercial objection to this type machine.

Another important result obtained by this arrangement of the absorber and circulator is that the circulating fan is removed from the flue 7 which has been the conventional position in prior arrangements. By removing the circulating unit from the flue 7, the depth of that flue may be materially decreased as the depth required to accommodate the cooling air flow is considerably less than the depth required to house the circulating unit. Consequently, an effective reduction in the overall depth of the unit is achieved without sacrificing either efficiency or function and any depth saved at this point is of material importance in enabling the designer to fit the cabinet within the maximum dimensions allowable in household machines.

Due to the fact that it is very difficult if not impossible to insure that the machines will be in an absolutely level position when installed in a household, the present invention provides an arrangement whereby non-leveling of the apparatus will not adversely affect the solution level in the apparatus and in particular will not ad-

versely affect the operation of the twin gas lift pump. As may readily be seen from Figure 2, the twin gas lift pump is adjacent the center of the compartment 4 as is the solution reservoir S. Moreover, the liquid supplied to the pump is taken from the bottom central portion of the solution reservoir S. It has been found that by placing the solution reservoir and twin gas lift pump adjacent the central portion of the compartment 4 and further by taking the liquid to be pumped from the bottom central portion of the solution reservoir that the inequalities normally encountered in domestic establishments will not adversely affect the twin gas lift pump and specifically will not cause sufficient difference in the liquid levels in the two legs of the pump to prevent the same from operating properly. It is not necessary to place these elements in the geometrical center of the compartment 4 because of the fact that the small inclination which may be given the part located adjacent the center due to an inequality of the apparatus is not sufficient to cause injurious effects from the operation of the system, whereas such inequalities would produce this result were the gas lift pump, for example, positioned in one corner of the compartment 4.

The refrigerating mechanism is carried upon a suitable frame mechanism indicated generally at 10 which rests upon and is suitably attached to the foot plate 9.

Thus, the present invention provides a refrigerating apparatus in which the circulating pump and solution reservoir are positioned in the central portion of the mechanism compartment whereby noise produced by these elements is effectively muffled within the compartment 4 and the apparatus is protected from undesirable results which might flow from installation of the same in a non-level position.

The arrangement of the absorber, that is, inclined downwardly and rearwardly within the compartment 4 to a position beneath the lower end of the air flue 7 facilitates this by allowing the gas lift pump and solution reservoir and circulating fan and its drive motor to be moved out of the normal path of cooling air through the apparatus and to provide an unobstructed path of flow of cooling air from a point adjacent the floor upwardly through the compartment 4 and over the air-cooled absorber A. Still further the arrangement of the air-cooled absorber A provides a path rearwardly of the compartment 4 and above the level of the absorber of constantly increasing cross-sectional area for air heated by passage over the absorber element which is then seeking an entrance to the flue 7 wherefore all the absorber tubes receive air not previously heated by passing over another absorber tube, are not obstructed by mechanical elements of the apparatus and the absorber is so arranged with respect to the chamber 4 and particularly the bottom wall of the compartment 2 that there is no choking effect on the air stream discharged by the absorber element.

Moreover, the flue 7, though narrow in depth as compared with previous constructions, is ample to take care of the quantity of air necessary to cool the apparatus adequately and is substantially unobstructed for its entire depth except for normally air-cooled elements. These factors all contribute to produce an absorption refrigerating machine which is highly efficient and reliable in operation and is simpler to manufacture than previous designs because the arrangement of the solution circuit and of the circulating mechanism

permits short direct connections between all parts of the apparatus located within the mechanism compartment.

5 While the invention has been described and illustrated in detail, various changes may be made in the arrangement, construction and proportion of parts without departing from the spirit of the invention or the scope of the appended claims.

I claim:

- 10 1. In a refrigerating apparatus, a cabinet having a storage chamber and an air cooling and mechanism chamber extending beneath and along one wall of said storage chamber, a three-fluid absorption refrigerating system associated with said cabinet including an evaporator in said storage chamber and an absorber, a generator and a condenser in said mechanism compartment connected in circuit, a power driven circulator connected to circulate an inert gas between said evaporator and said absorber, said power driven circulator being located in said mechanism chamber beneath said storage chamber adjacent the central portion thereof to reduce the effect of noise produced by said circulator externally of said cabinet, and sound absorbing material on certain of the walls of said mechanism chamber.

15 2. In a refrigerating apparatus, a cabinet having a storage chamber and an air cooling and mechanism chamber extending beneath and along one wall of said storage chamber, a three-fluid absorption refrigerating system associated with said cabinet including an evaporator in said storage chamber and an absorber, a generator and a condenser in said mechanism compartment connected in circuit, a gas lift pump in said circuit arranged to circulate solution between said generator and said absorber, said pump being located in said mechanism chamber beneath said storage chamber and adjacent the central portion thereof whereby deviations from level installation of the apparatus will have a minimum effect on said pump.

20 3. In a refrigerating apparatus, a cabinet having a storage chamber and an air cooling and mechanism chamber extending beneath and along one wall of said storage chamber, a three-fluid absorption refrigerating system associated with said cabinet including an evaporator in said storage chamber and an absorber, a generator and a condenser in said mechanism compartment connected in circuit, a gas lift pump in said circuit arranged to circulate solution between said generator and said absorber, a solution reservoir connected to the inlet of said pump, said pump and said reservoir being located in said mechanism chamber beneath said storage chamber and adjacent the central portion thereof whereby deviations from level installation of the apparatus will have a minimum effect on said pump.

25 4. A refrigerating device comprising a cabinet structure including a refrigerating chamber and a mechanism compartment having a lower section underlying said chamber and arranged for free flow of cooling air thereinto from below and an upstanding section opening into said lower section, an absorption refrigerating apparatus associated with said cabinet structure comprising an inert fluid circuit including an evaporator in said chamber and an absorber in said compartment, an absorbing fluid circuit including said absorber and a generator positioned in said compartment and means for liquefying refrigerant vapor produced by said generator and for supplying the liquid to said evaporator, and a power driven circulator included in said inert fluid cir-

cult and positioned in said compartment beneath the central portion of said refrigerating chamber and above said generator.

5. A refrigerating device comprising a cabinet structure including a refrigerating chamber and a mechanism compartment having a lower section underlying said chamber and arranged for free flow of cooling air thereinto from below and an upstanding section opening into said lower section, an absorption refrigerating apparatus associated with said cabinet structure comprising an inert gas circuit including an evaporator in said chamber and an absorber in said compartment, a solution circuit including said absorber and a generator positioned in said compartment, means for liquefying refrigerant vapor produced by said generator and for supplying the liquid to said evaporator, a solution reservoir in said solution circuit, and a gas lift solution circulating pump in said solution circuit, said pump being connected to receive solution from the bottom central portion of said reservoir and to discharge solution into said absorber, said pump and said reservoir being located adjacent the central portion of that section of said compartment which underlies said chamber.

6. A refrigerating device comprising a cabinet structure including a refrigerating chamber and a mechanism compartment having a lower sec-

tion underlying said chamber and arranged for free flow of cooling air thereinto from below and an upstanding section opening into said lower section, an absorption refrigerating apparatus associated with said cabinet structure comprising an inert gas circuit including an evaporator in said chamber and an absorber in said compartment, a solution circuit including said absorber and a generator positioned in said compartment, 10 means for liquefying refrigerant vapor produced by said generator and for supplying the liquid to said evaporator, said absorber comprising a plurality of conduits positioned at different elevations, said conduits as a group extending from a point beneath said chamber downwardly in the direction of said upstanding section of said compartment, a power driven circulator included in said inert gas circuit and positioned in said compartment beneath said chamber, a solution reservoir in said solution circuit, and a gas lift solution circulating pump in said solution circuit, 15 said pump being connected to receive solution from the bottom central portion of said reservoir, and to discharge solution into said absorber, said pump and said reservoir being located adjacent the central portion of that section of said compartment which underlies said chamber.

RALPH C. OSBORN.
